UNITED STATES PATENT OFFICE.

WILLIAM C. IRVIN, OF SAN FRANCISCO, CALIFORNIA.

METALLIC SHIPPING-BARREL.

1,398,298.

Specification of Letters Patent. Patented Nov. 29, 1921.

Application filed February 12, 1921. Serial No. 444,522.

To all whom it may concern:

Be it known that I, WILLIAM C. IRVIN, a citizen of the United States, residing at the city and county of San Francisco and State 5 of California, have invented certain new and useful Improvements in Metallic Shipping-Barrels, of which the following is a specification.

The present invention relates to that type 10 of metallic barrels which are formed in halves and shipped to the consumer thereof in a nested condition, being re-assembled at a later period for the shipment of such commodities as cocoa and other oils, which are 15 usually transported from foreign countries. When barrels of this type are re-assembled, great difficulty has been experienced in the formation of a hermetic seal or non-leaky circumferential joint union between the two 20 sections of the barrel, and it is to this feature which the herein invention more particularly relates, as well as to general constructive features of the barrel sections themselves.

25 To comprehend the invention, reference should be had to the accompanying sheet of drawings, wherein:—

Figure 1 is a perspective view of the assembled barrel.

30 Fig. 2 is a vertical sectional view of half of a barrel, illustrating its companion half nested therein for shipment.

Fig. 3 is a broken detail vertical sectional view taken on the line 3—3, Fig. 4 of the 35 drawings, disclosing the manner of securing a head or end to the chime of a barrel section.

Fig. 4 is a sectional view taken on the line 4—4, Fig. 3 of the drawings, and viewed in 40 the direction of the arrows.

Fig. 5 is a broken vertical sectional view taken on the line 5—5, Fig. 1 of the drawings.

Fig. 6 is a broken vertical sectional view 45 taken on the line 6—6, Fig. 1 of the drawings.

Fig. 7 is a broken sectional view taken on the line 7—7, Fig. 1 of the drawings, illustrating the manner of uniting the barrel 50 sections for the forming of a circumferential hermetic sealed joint union.

Fig. 8 is a broken perspective view of the lower edge portion of the upper section of the barrel.

55 Fig. 9 is a broken perspective view of the

upper edge portion of the lower section of the barrel.

Fig. 10 is a broken perspective view of the split securing clamp ring or band for uniting circumferentially the two halves of the 60 barrel.

Fig. 11 is a broken detail view disclosing the tightening ring for drawing the clamp band into position for securely uniting the barrel sections end to end. 65

Fig. 12 is a broken detail view illustrating a modified form of uniting the ends of the split securing clamp band.

Fig. 13 is a broken top plan sectional view taken on the line 13—13 Fig. 12 of the drawings. 70

In the drawings, Figs. 1 and 2 thereof, the numerals 1 and 2 are used to designate the top and bottom halves respectively of a metallic barrel. To the upper or top section or 75 half 1 is permanently secured or attached the head end 3, provided with the usual filling opening 4, and to the lower half 2 is permanently united the bottom end 5. The chime of each barrel section terminates in an 80 inwardly projected angular shaped circumferential flange 6 forming an annular seat into which is forced for seating a correspondingly shaped circumferential flange 7 projected from the ends or bottoms, there 85 being held within the groove formed by such upset flange, of the ends a reinforcing band or ring 8 for strengthening the ends of the barrel when the sections are assembled.

Each barrel section is formed gradually 90 increasing in diameter from the chime end thereof—so that one section will nest within another for the purpose of shipment when the halves are unassembled. The ends or heads are applied to the sections by being 95 forced downwardly from the inside thereof until the circumferential flange 7 is firmly seated within the annular groove or channel formed by the circumferential angular flange 6. 100

The enlarged end of the barrel section 1 is formed with an offset rim 9, which provides an exterior circumferential shoulder 10, and said rim serves as a tongue extension of the section 1, for interlocking with the 105 section 2 on an assembling of the barrel sections—as hereinafter described.

To the section 1 above the shoulder 10 is riveted or welded a reinforcing locking hoop or band 11, which in depth is sufficient to 110

partly overlie the rim 9 and strengthen the same.

The upper end of the barrel section 2 is reinforced by the hoop or band 12 riveted or 5 welded thereto, the upper inner face portion of said band being offset in order to provide in conjunction with the outer wall of the barrel section an annular groove or channel 13, into which seats the tongue extension 9 10 of the section 1 on the barrel section being assembled.

Each reinforcing hoop or band 11—12, on its upper edge is downwardly inclined outwardly in order to provide a beveled seat *a* 15 to receive the inwardly inclined faces *b* of a channeled split lock or clamp band 14.

To one end of the said split lock or clamp band is permanently secured, by riveting or welding, a tongue extension 15, which on the 20 split ring being fully closed around the united barrel sections overlaps and is secured to the opposite end of said band by spot welding, Fig. 10 of the drawings.

Another manner of uniting the ends of the 25 split clamp band is by means of a fastening lug 16, Figs. 12 and 13 of the drawings, one end of which is passed through an opening 17 formed adjacent one end of the clamp band, and bent over for attachment. The 30 opposite end of the lug is slightly inclined, so that as the split ring is drawn together such end will ride upon the inclined face of the lug opening 18 in the opposite end of the split ring, and is then bent over to hold the 35 ends of the split ring fastened together. Preference, however, is given to the former described means of uniting the ends of the split locking ring, but the manner of uniting the same is an immaterial feature.

40 Within the circumferential groove or channel 13 formed by the offset portion of the hoop or band 12 of the lower half or section 12 of the barrel is fitted a gasket ring 19, Fig. 7 of the drawings, which is compressed 45 by the tongue extension 9 of the upper half or section 1, on the barrel sections being drawn together in order to make a tight joint or hermetic seal union between the said parts.

50 When it is desired to store liquids or semi-liquids within the container for shipment or transportation to distant points, as for instance, from the Orient to this country, the barrel is assembled by placing the open end 55 of the sections 1—2 end to end with the projecting extension or circumferential tongue 9 of the section 1 fitted within the circumferential groove or channel 13 of the lower section or half 2. The channeled split fastening clamp or band 14 is then placed around the loosely united barrel sections to 60 cover the circumferential seam joint, the beveled faces *b* thereof bearing on the inclined faces *a* of the reinforcing hoops 11 65 and 12 of the sections 1 and 2 respectively.

There is then placed over the split ring 14 a tightening split ring 20, one end of which carries a holding yoke 21 and the opposite end an ear 22. Through the holding yoke 21 and the ear 22 works a tightening screw 70 bolt 23, which when the securing nut 24 is screwed onto the extended threaded end of the bolt 22 draws together the ends of the tightening ring 20, which in turn compresses the clamp band 14 and draws together the 75 ends thereof. As the fastening clamp band 14 is compressed circumferentially by the drawing together of the split ring 20, the beveled faces *b* thereof riding on the inclined faces *a* of the hoops 11 and 12 exert a downward pressure thereon and draws the barrel sections 1 and 2 firmly together endwise, the tongue 9 of the section 1 compressing the packing ring 19 to form a hermetically sealed circumferential joint union between the 85 sections. With the parts in this position, the tongue extension 15 projecting from one end of the split clamp band 14 will overlie its opposing end, and is spot welded thereto to hold the clamp or band 14 in fastened position.

After the filled barrel or container has been delivered to its proper destination, and its contents removed, it is only required in order to dis-assemble the barrel that the 95 spot welded union between the tongue 15 and the clamp 14 be destroyed or ruptured, when the said clamp may be readily removed and the barrel sections separated to be nested for re-shipment, it being understood that the 100 channeled split clamp band or ring 14 may be reshipped with the nested sections of the container, or a new one supplied with each re-assembling of the barrel sections.

By the described invention, there is provided for the assembling of metallic barrel sections in such a manner as to provide a hermetically sealed circumferential joint union between the barrel sections, thereby 110 providing against the contents of the barrel 110 or container leaking out at such joint of union. By the described means, the barrel sections may be quickly assembled when required for use and equally so dis-assembled for purposes of shipment in a knocked down 115 nested condition.

Having thus described my invention what I claim as new and desire to secure by Letters Patent of the United States is:—

A metallic barrel for the shipment of oils or similar commodities, the same comprising an upper and lower conical section, adapted to be nested for shipment, the upper section being offset at its open end to provide an outer circumferential shoulder, a reinforcing 120 locking hoop secured to said section to overlie the shoulder thereof, a reinforcing locking hoop secured to the open end of the lower section and offset on its inner face to provide with the face of said section an annular 125 130

groove for the reception of the offset portion of the upper section on an assembling of the barrel sections, a packing ring within said annular groove, the upper face of the reinforcing hoop for upper section of the barrel and the lower face of the reinforcing hoop for the lower section of the barrel being downwardly inclined outwardly, a channeled split lock band adapted to embrace [10 the reinforcing hoops and provided with inclined faces for engagement with the inclines of said hoops to draw together the barrel sections on circumferential pressure being applied to said lock band, and means for uniting the ends of the lock band on the 15 barrel sections being assembled.

In testimony whereof I have signed my name to this specification.

WILLIAM C. IRVIN.
